UNITED STATES PATENT OFFICE.

FELIX A. CARNEY, OF MEMPHIS, TENNESSEE.

HANDLE-TURNING MACHINE.

1,147,372.

Specification of Letters Patent. Patented July 20, 1915.

Application filed September 28, 1914. Serial No. 863,885.

To all whom it may concern:

Be it known that I, FELIX A. CARNEY, a citizen of the United States, residing at Memphis, in the county of Shelby and State 5 of Tennessee, have invented new and useful Improvements in Handle-Turning Machines, of which the following is a specification.

This invention relates to improvements in wood working machines and more particularly to a machine for turning the ends of tools, brooms, mops, or other handles.

It is the object of this invention to provide a machine to which may be fed the handles as they come from the lathe and 15 from which the handles are discharged with the end completely turned.

The advantages of such a machine are obvious as the machine works automatically. The construction is extremely simple and 20 does away with all manual handling of the articles as a step by step conveyer successively advances each handle toward the cutter, a positive gripping means holds the handle opposite the cutter which is advanced against the rough end of the handle and withdrawn automatically from the turned end and the finished handle discharged.

While the preferred forms of this invention 25 are illustrated upon the accompanying drawings, yet it is to be understood that minor detail changes may be made without departing from the scope thereof.

Figure 1 is a view in side elevation of a 30 complete machine constructed in accordance with this invention. Fig. 2 is a top plan view of the same. Fig. 3 is a transverse sectional view taken on the line 3—3 of Fig. 1 looking in the direction of the arrow. Fig. 4 is a similar view taken on the line 4—4 looking in the direction of the arrow. Fig. 5 is a fragmentary view in elevation of one end of the machine. Fig. 6 is a partial longitudinal vertical sectional view 45 taken on the line 6—6 of Fig. 2.

The handles as they come from the lathe are manually fed end to end into the guide 1 extending across the front of the machine. The machine side of the guide is provided 50 with guards 2 adjustable, in accordance with the length of the handles to be turned, to retain the handles passing through the guide until the farther end is reached when the handle is discharged by gravity upon 55 a step by step conveyer. This conveyer is arranged transversely of the frame of the

machine and comprises a plurality of fixed notched members 3 extending from below the guide upward at an angle with the bottom of one notch in line with the cutter. 60 On the adjacent sides of each pair of fixed members 3 are arranged similar movable members 4 the upper and lower ends of each pair of the movable members being connected by a brace 5 having a central depending arm 6. Operating shafts 7 are mounted in bearings upon the under side of the fixed members at top and bottom which shafts are provided with a sprocket and a crank arm 8 pivotally connected to the arm 6 so that 65 when the shafts are rotated in the same direction an oscillating movement is imparted to the members 4 and a handle, shown in dotted lines on Fig. 3, resting upon the notches of the fixed member will be engaged 70 and advanced upward one notch upon each oscillation of the movable members.

Between the far end of the machine frame and adjacent the contiguous fixed member 3 of the conveyer a transverse guide in the 75 form of a plate 9 is mounted upon a transverse support and this transverse guide will be engaged by the end of the handle to be finished upon its discharge from the longitudinal guide 1 so that upon its upward 80 travel upon the conveyer each handle will occupy the same relative position when it reaches the center notch of the fixed member. Opposite this center notch a cutter head 10 is carried upon a longitudinal shaft 11 85 mounted to both rotate and travel longitudinally in bearings upon the end of the machine frame and transverse support. This shaft is provided with a fly wheel 12 and a belt pulley 13 adapted to be connected to a 90 power shaft by a belt. As each handle is lowered into the center fixed notch it passes between two jaw heads 14 rotatably mounted upon the ends of two jaw arms 15 which grip and hold the handle while the cutter head advances and turns the end. Upon the withdrawal of the cutter head the jaws open and release the finished handle which is advanced 95 a step up the conveyer and a new handle placed between the jaws.

The cutter head 10 is advanced and withdrawn and the gripping jaws 14 are operated from a longitudinal driven shaft 16 centrally mounted in bearings upon the lower portions of the machine frame. A driving 100 shaft 17 parallel to the driven shaft is mounted to one side thereof in bearings

upon the farther end of the frame and transverse support with a belt pulley 18 upon the end extending beyond the end of the frame. The driving shaft 17 is provided with a 5 pinion 19 meshing with a gear wheel 20 upon the driven shaft and the driving shaft is preferably driven in the reverse direction from the cutter shaft 11 by a twisted belt from a power shaft 21, the gear and pinion 10 connection between the driven and driving shafts reducing the speed of the driven shaft.

The cutter shaft 11 is reciprocated by means of a cam 22 upon the driven shaft 16 between the conveyer and transverse support 15 engaging one end of a bell crank lever pivotally mounted at its apex upon a transverse pin 23 and having its other end forked to engage a sleeve 24 therefor upon the cutter shaft between its belt pulley and fly 20 wheel. The cam 22 is preferably in the form 25 of a circle with a cutoff flat 25 which will allow the cutter head to be advanced to engage the end of the handle and completely turn the end before it is withdrawn by the 30 rotation of the cam, the circular portion maintaining the cutter head in the retracted position until the finished handle has been removed and a new one substituted. The lower end of the bell crank lever is provided 35 with a roller 26 traveling about the cam and is held in contact therewith by means of an arm 27 pivoted at one end to the upper portion of the transverse support through which this arm of the lever freely passes and having a weight, or other means, to hold the roller on the cam.

In order to regulate and adjust the amount of advance of the cutter head 10 the bell crank lever is preferably constructed in 40 two parts, the lower arm 28 being pivoted to the transverse pin 23 and provided with a flat upper surface thereover while the lower end of the upper arm 29 is branched to straddle the lower arm and the ends pivoted to the transverse pin. Between the 45 branches the upper arm is provided with a projection 30 on each side parallel to and overlying the flat surface of the lower arm. The angular relation of the two arms may 50 be adjusted and held by set screws 31 engaging the projections and flat surface on either side of the pivot pin.

The gripping jaws 14 are also operated through a cam 32 upon the driven shaft 16 55 mounted intermediate the ends of the conveyer. The jaw arms 15 are in the form of oppositely extending bell crank levers, pivoted at their apexes by longitudinal pins in a transverse support between the fixed conveyer members adjacent the chuck end. The upper ends carry the pivoted horizontal jaw heads 14 and the lower ends are connected by pivoted pins 33 to a sleeve 34 about the 60 end of a floating longitudinal shaft 35. The opposite end of the floating shaft is mount-

ed in a slide bearing 36 upon the end of the machine frame and is normally held in depressed position by a weight or spring. Intermediate the ends of the floating shaft 35 a roller 37 is mounted which rides upon the 70 cam 32 upon the driven shaft. This cam is preferably in the form of an eccentric so shaped that as the cutter head advances the end sleeve 34 on the floating shaft will rise up upon the jaw arms 15 so that the jaw heads will grip the handle and hold it until the end is turned and upon the withdrawal of the cutter head the jaw heads will open. 75

A sprocket 38 is provided upon the driven shaft in line with the sprockets on the longitudinal conveyer shafts which are driven in the same direction by a chain passing over them. The upper ends of the fixed members of the conveyer are provided with an incline 39 to discharge the finished handles 80 into a proper receptacle. 85

What I claim is:

1. In a handle end turning machine, a longitudinally movable shaft, a cutter head on one end thereof, means for rotating said cutter shaft, a power driven shaft, means actuated thereby for advancing and withdrawing said cutter shaft, means actuated thereby for conveying handles by said cutter head parallel with said cutter shaft with their ends in position to be engaged by the cutter head upon its advance and means for temporarily holding the handle as it passes the cutter head until its end has been turned thereby, comprising a pair of jaw heads carried upon pivoted jaw arms having oppositely extending angular projections beyond their pivot points, a floating shaft, a sleeve on one end thereof having pivoted connecting rods pivotally engaging the ends of said angular projection, said floating shaft mounted in a vertically traveling bearing at the other end and having a roller rotatably mounted thereon intermediate its ends, a cam upon the driven shaft upon which the roller travels and so adapted that as a handle comes in line with the cutter head the jaws will grip it and hold it during the turning of the end and then release it and grip the next one advanced. 100

2. In a handle end turning machine, a frame, a central longitudinal driven shaft mounted therein, a driving shaft mounted at one side thereof, a pinion and gear wheel connection between the two reducing the 105 speed of the driven shaft, a driving belt pulley upon the driving shaft, a longitudinally movable shaft mounted at one end of the frame, a cutter head on the inner end thereof, a belt pulley and a fly wheel and bearing mounted thereon, an inclined conveyer supported upon the remainder of the frame, a horizontal guide above the lower end of the conveyer through which handles are introduced end to end for depositing handles 110

upon the conveyer, an operating connection from the conveyer to the driven shaft to engage, lift and convey handles and discharge them over the upper end, a pair of gripping jaws in line with the cutter head, a cam on the driven shaft, a pivoted bell crank lever having one end held in engagement with said cam and the other engaging the bearing of the cutter shaft for advancing and withdrawing the cutter head, a guide for the handle ends to position the one over the gripping jaw to be turned upon advance of the cutter head, a second cam on the driven shaft, a floating shaft having a rotatable roller in engagement therewith with a bearing upon the inner end and the other end mounted in a traveling bearing,

said gripping jaws mounted upon pivoted oppositely disposed bell crank lever arms and connecting rods pivoted at their ends 20 to the lower bell crank arms and bearing respectively, said cams and connections with the driven shaft so constructed as to allow of a handle to be gripped during the turning of its end by the advance of the cutter head 25 and then be released, the cutter head withdrawn and the finished handle moved up upon the conveyer and the operation repeated upon the handle next below on the conveyer.

FELIX A. CARNEY.
